UNITED STATES PATENT OFFICE.

FRANK HARRINGTON, OF HARTFORD, CONNECTICUT, ASSIGNOR TO THE SMYTH MANUFACTURING COMPANY, OF HARTFORD, CONNECTICUT, A CORPORATION OF CONNECTICUT.

FABRIC-SUPPLYING DEVICE FOR BOOK-SEWING AND SIMILAR MACHINES.

933,439.

Specification of Letters Patent. Patented Sept. 7, 1909.

Application filed February 28, 1905. Serial No. 247,791.

To all whom it may concern:

Be it known that I, FRANK HARRINGTON, a citizen of the United States, residing at Hartford, county of Hartford, and State of Connecticut, have invented certain new and useful Improvements in Fabric-Supplying Devices for Book-Sewing and Similar Machines, fully described and represented in the following specification and the accompanying drawings, forming a part of the same.

This invention relates to certain improvements in fabric supplying devices for book sewing and similar machines.

In assembling signatures into books, it is customary, with certain classes of books, to employ a band of fabric, such as crash, which overlies the back of the book, the signatures being successively secured to the fabric. In what are known as book stapling machines, each signature is stapled to the fabric band. In book sewing machines, the signatures are sewed together, the sewing passing through the band of fabric. It is customary to supply the fabric to book sewing and stapling machines from a roll, and after a sufficient number of signatures to form the book has been secured to the fabric, the fabric is cut. It is usual, however, to leave extensions or tabs of the fabric on each side of the book thus formed, these extensions or tabs being used to secure the book in its cover. In the operation of book sewing and stapling machines, it is customary, in order to provide for these extensions or tabs of the fabric, to insert between each group of signatures which forms a book, a wooden spacing block which provides the necessary length of fabric to form extensions on the adjacent sides of two successive books and at the same time affords a surface over which the operator can run a knife to separate the books. The use of these spacing blocks is, however, objectionable for the reason that it requires the time of the operator to put the blocks in position, and for the further reason that they take up space in the machine and require the books to be frequently removed.

It is the object of this invention to provide improved fabric supplying devices for book sewing and stapling machines which devices include means for forming a fold of fabric between signatures which fold may

be afterward cut to separate successive signatures or groups of signatures into books, thus avoiding the necessity for using spacing devices heretofore employed for this purpose.

With this and other objects in view, the invention consists in certain constructions, and in certain parts, improvements and combinations as will be hereinafter fully described and specifically pointed out.

Referring to the drawings—Figure 1 is a plan view illustrating one form of fabric supplying device embodying the invention. Fig. 2 is a side view of the construction shown in Fig. 1, certain parts being shown in section. Fig. 3 is a section. Figs. 4 and 5 are sectional detail views illustrating the mode of action of the fold forming device, and Fig. 6 is a front elevation of the fabric supplying device applied to a book sewing machine.

Referring to the drawings, the construction which has been selected to illustrate a concrete embodiment of the invention is shown in connection with a book sewing machine of the general type illustrated in Patent No. 435,613, granted September 2, 1890, to the Smyth Manufacturing Co. of Hartford, Conn., as the assignee of J. R. Reynolds and A. I. Jacobs.

The construction embodying the invention will include suitable means for supplying fabric, and preferably this means will include a core on which the fabric is mounted. In the particular construction shown, a core 1 of wood or other suitable material is employed for this purpose, this core being supported on a shaft 2 which in turn is mounted in bearings 3 formed in hangers which are made integral with the side frames 4 of the machine. The roll 1 is or may be formed with a cleft 5 into which the end of the fabric is inserted, as is usual in such constructions.

In the best constructions embodying the invention, a tension device will be employed, which device may be of any suitable character. In the particular construction shown, the tension device includes a bar 6 over which the fabric is led (see Fig. 3), and a bar 7, which bar is mounted in arms 8 pivoted on the bar 6. A light spring 9 is or may be employed to exercise a tensioning pull on the arms 8 and bar 7. If desired, there may

also be employed a bar 10 mounted in arms 11, these arms being also pivoted on the bar 6. This bar 10 when employed rests on the fabric roll, and a spring 12, if desired, may be employed which will hold the bar to its 5 duty.

In the particular construction shown, the side frames 4 are held together by a cross web 13, though the construction may be 10 varied in this respect, if desired, and this web is channeled as at 14, to form a passage for the fabric.

Machines with which the improved fabric supplying device is employed, will include 15 means for securing the fabric to the signatures, and in some machines these means will also operate to secure the signatures together. The particular machine which has been selected to illustrate the operation of the improved fabric supplying device is of the latter type, the fabric being secured to the signatures and the signatures being secured to each other by semi-circular needles 15 mounted on arbors 16, the needles being held 20 in position by collars 17 secured on the arbors by screws 18.

The particular means for operating the needles and for supplying thread to the same are not illustrated inasmuch as an illustration 30 and description of the same will not assist in an understanding of the present invention.

Machines with which the improved fabric supplying device is employed will further 35 include some means for holding the signatures in position while the securing means act, and these means may also act to position the signatures. In the particular machine selected to illustrate the operation of the improved fabric supplying device, the signatures are successively brought into position and supported by a signature carrying bar 19 which may be of any well-known type, and which may be moved by any desired 40 means to bring the signatures into proper position. The signatures after being operated upon by the securing means are advanced and supported on a table 20 which may be of any preferred construction.

50 The fabric, in the particular construction illustrated, is led from the channel 14 before referred to, to the signatures, marked 21, and as the signatures are brought successively into position by the signature carrying bar or other means, the fabric is secured to the signatures by the securing means. When a sufficient number of signatures 55 to form a book have been secured to the fabric, a fold is formed in the fabric, 60 means which may be widely varied in construction being employed for this purpose.

In the particular machine illustrated, the fold forming means includes a shaft 22 journaled in the side frames, this shaft 65 having a squared central portion 23 and

being provided with suitable fabric engaging means. The particular means illustrated consist of a plurality of toothed plates 24, though any other form of fabric engaging means may be used. Four of these toothed plates are employed, although 70 this number may be varied as desired.

In the best constructions, in order to form the fold in the fabric, the fold former, whatever be its particular construction, will be given a movement, and when, as in the construction selected to illustrate the invention, the fold former is a shaft, this movement will be a rotary movement. This movement may be effected in any desired manner, and the means for effecting it will, in the best 75 constructions, be under the control of the operator, so that the fold former may be brought into operation at varying times, according to the number of signatures which 80 are to be secured to the fabric before the fold is made. In the particular construction illustrated, the shaft 22 is provided with a gear 25 which meshes with a spiral gear 26 mounted on a shaft 27 journaled in a long bearing 28 formed integral with a block 29 which is secured by screws 30, or in any other suitable manner, to one of the side frames 4. This shaft 27 is or may be provided with a handle 31 by which it is 85 turned, the handle being secured to the shaft by means of a pin 32 or in any other suitable manner. In the particular machine illustrated, the parts are so proportioned that the shaft 22 is given a quarter-turn for 90 each fold forming operation, and in order to effect this quarter turn, the shaft 27 is given a complete revolution. In order to notify the operator that the shaft 27 has made a complete revolution, there is, or may 95 be provided, a spring pin 33 which engages in a notch formed in a collar 34 on the long bearing 28. The engagement between the pin and the notch is such that the pin will 100 readily slip out of the notch when force is 105 applied to the handle to turn it, the pin snapping back into the notch when a complete revolution of the shaft has been made.

In the best constructions, a guide will be 110 employed to insure the positive engagement of the fabric engaging device with the fabric. While this guide may be varied in construction, and will be varied according to the character of the engaging device employed, in the particular construction illustrated, this guide consists of a curved extension 35 which may be conveniently formed integral with the cross rib 13. This guide is or may be provided with grooves 36 into 115 which the teeth of the plates 24 project.

In the operation of the device, after the desired number of signatures has been secured to the fabric, the shaft is rotated and the teeth of the plates 24 engaging the 120 fabric, feed it forward and throw it down 125

into a loop. This operation is illustrated in Fig. 4, the parts as there shown being illustrated in the position they occupy just after the fold forming operation is begun.

5 Machines with which the improved fabric supplying device is employed will usually be provided with means for advancing the signatures. In the particular construction employed to illustrate the invention, this 10 advancing movement of the signatures is effected by the fold forming means. The construction by which the fold forming means is employed to advance the signatures and is given the necessary movements 15 for this purpose, may be of any suitable character. In the particular construction illustrated, the fabric feeding device is mounted on slides 37 and these slides are, by any suitable mechanism, given a movement 20 toward and away from the signatures. The mechanism employed for moving these slides may include racks 37^a formed on or suitably secured to the slides 37, these racks being engaged by pinions 37^b mounted on a 25 cross-shaft suitably supported on the frame of the machine, this mechanism being similar to that employed for moving similar slides carrying a presser bar in the Reynolds and Jacobs patent above referred to. These 30 slides will, of course, be operated after each signature has been secured to the fabric and this movement of the slides is utilized after each fold forming operation to lay the fold. The position of the parts after a fold has 35 been laid is illustrated in Fig. 5, the folds formed in the fabric being marked 38 in this figure.

In the best constructions embodying the 40 invention means will be employed to hold the fold after it is laid, thus preventing it from springing open after the fold laying device has retreated and thus getting in the way of the succeeding signature. In the particular construction shown, this holding 45 function is effected by means of fingers 39, these fingers being mounted on a slotted bar 40 which is given a rising and falling movement. This bar 40 is mounted on the front 50 of an overhanging arm 41 indicated in Fig. 6, which serves to support the sewing mechanism. The means for operating this bar 40 may include a pivoted lever 40^a connected to an extension 40^b of the slide by 55 means of a link 40^c. This lever may be operated from a suitable cam, not shown. The plates 24 before referred to are or may be provided with recesses 42 into which the 60 fingers enter when the fingers are in their downward position. In order to prevent the bottom of the signatures from falling outward as the signature carrying bar retreats, a stop bar 43 is or may be provided, this bar being adjustably mounted on rods 44 depending from the side frames 4.

65 While the construction shown embodying

the invention is believed to be the best form for carrying the invention into effect, it is to be understood that changes and variations may be made therein without departing from the invention. While, furthermore, the construction embodying the invention is illustrated in connection with book sewing machines of a particular type, it is to be understood that it may be used with other types of book sewing machines, 70 and also with other forms of machines, such, for instance, as wire stapling machines, in which signatures are to be secured to fabric. It will also be understood that while the particular devices illustrated are 75 shown operating in connection with a single band of fabric which is applied to the back of a book, the invention is not limited to such use but may be employed in connection with the application of a plurality of bands or 80 tapes, and that the term "fabric" herein used applies not only to a single band or tape but to a plurality of such bands or 85 tapes.

What is claimed is:—

1. In an organized machine for securing 90 signatures together to form books, the combination with signature supporting and advancing means, of means for supplying fabric to the backs of the signatures and for 95 securing it thereto, a fold former, and means for operating the former to produce a fold in the fabric between successive groups of signatures.

2. In an organized machine for securing 100 signatures together to form books, the combination with signature supporting and advancing means, of means for supplying fabric to the backs of the signatures and for 105 securing it thereto, a fold former, means for operating the former to produce a fold in the fabric between successive groups of signatures and a fabric guide—cooperating with the former.

3. In an organized machine for securing 110 signatures together to form books, the combination with signature supporting and advancing means, of means for supplying fabric to the backs of the signatures and for 115 securing it thereto, a fold former, means for operating the former to produce a fold in the fabric between successive groups of signatures and a tension device co-operating with the former.

4. In an organized machine for securing 120 signatures together to form books, the combination with signature supporting and advancing means, of means for supplying fabric to the backs of the signatures and for 125 securing it thereto, a fold former, means for operating the former to produce a fold in the fabric between successive groups of signatures, a fabric guide and tension device co-operating with the former.

5. The combination with signature sup-

porting means, of means for supplying fabric to the backs of the signatures and for securing it thereto, a fold former, and means for giving it a rotary movement to form a fold of fabric between the signatures.

6. The combination with signature supporting means, of means for supplying fabric to the backs of the signatures and for securing it thereto, a fold former, means for 10 operating the former to form the fold, and a fold retaining means.

7. The combination with signature supporting means, of means for supplying fabric to the backs of the signatures and for 15 securing it thereto, a fold former, means for operating the former to form a fold, a fabric guide coöperating with the former, and fold retaining means.

8. The combination with signature supporting means, of means for supplying fabric to the backs of the signatures and for 20 securing it thereto, a fold former, means for operating the former to form a fold, a fabric guide coöperating with the former, fold retaining means, and a tension device.

9. The combination with signature supporting means, of means for supplying fabric to the backs of the signatures and for 25 securing it thereto, and a rotary fold former having fabric engaging devices.

10. The combination with signature supporting means, of means for supplying fabric to the backs of the signatures and for 30 securing it thereto, a rotary fold former having a plurality of fabric engaging devices, and a fabric guide coöperating with the former.

11. The combination with signature supporting means, of means for supplying fabric to the backs of the signatures and for 35 securing it thereto, a rotary fold former having fabric engaging devices, a fabric guide coöperating with the former, and a tension device.

12. The combination with signature supporting means, of means for supplying fabric to the backs of the signatures and for 40 securing it thereto, a rotary fold former having a plurality of fabric engaging devices, and means under the control of the operator for 45 causing said devices to successively engage the fabric and form folds therein.

13. The combination with signature supporting means, of means for supplying fabric to the backs of the signatures and for 50 securing it thereto, a rotary fold former having a plurality of fabric engaging devices, means under the control of the operator for causing the devices to successively engage the fabric and form folds therein, and a fabric guide coöperating with the former.

14. The combination with signature supporting means, of means for supplying fabric to the backs of the signatures and for 55 securing it thereto, a rotary fold former having a plurality of fabric engaging devices,

means under the control of the operator for causing the devices to successively engage the fabric and form folds therein, a fabric guide coöperating with the former, and a tension device.

15. The combination with signature supporting means, of means for supplying fabric to the backs of the signatures and for securing it thereto, a rotary fold former having a plurality of fabric engaging devices, 75 means for operating the former to cause the devices to successively engage the fabric and form folds therein, and a fold retaining device.

16. The combination with signature supporting means, of means for supplying fabric to the backs of the signatures and for securing it thereto, a rotary fold former having a plurality of fabric engaging devices, 80 means for operating the former to cause the devices to successively engage the fabric and form folds therein, a fold retaining device, and a fabric guide coöperating with the former.

17. The combination with signature supporting means, of means for supplying fabric to the backs of the signatures and for securing it thereto, a rotary fold former having a plurality of fabric engaging devices, 85 means for operating the former to cause the devices to successively engage the fabric and form folds therein, a fold retaining device, a fabric guide coöperating with the former, and a tension device.

18. The combination with means for successively positioning and supporting signatures, of means for supplying fabric to the backs of the signatures and for securing it thereto, a fold former, and means for operating the former to form folds.

19. The combination with means for successively positioning and supporting signatures, of means for supplying fabric to the backs of the signatures and for securing it thereto, a fold former, means for operating 100 the former to form folds, and a fabric guide coöperating with the former.

20. The combination with means for successively positioning and supporting signatures, of means for supplying fabric to the 105 backs of the signatures and for securing it thereto, a fold former, means for operating the former to form folds, a fabric guide coöperating with the former, and a tension device.

21. The combination with means for successively positioning and supporting signatures, of means for supplying fabric to the backs of the signatures and for securing it thereto, a fold former, means for giving the 110 fold former a movement to advance the signatures after the securing devices have acted, and means for giving the former a rotary movement to form the fold in the fabric.

22. The combination with means for suc- 115

- cessively positioning and supporting signatures, of means for supplying fabric to the backs of the signatures and for securing it thereto, a fold former, means for giving the 5 fold former a movement to advance the signatures after the securing devices have acted, means for giving the former a rotary movement to form the fold in the fabrics, and a fabric guide coöperating with the former.
- 10 23. The combination with means for successively positioning and supporting signatures, of means for supplying fabric to the backs of the signatures and for securing it thereto, a fold former, means for giving the 15 fold former a movement to advance the signatures after the securing devices have acted, means for giving the former a rotary movement to form the fold in the fabric, a fabric guide coöperating with the former, a tension 20 device, and a fold retaining device.
24. The combination with means for successively positioning and supporting signatures, of means for supplying fabric to the backs of the signatures and for securing it thereto, a fold former having a plurality of 25 fabric engaging devices, a fabric guide coöperating with the former, means for giving the fold former movements after the securing device has acted to advance the signatures, and means for giving the fold former 30 rotary movements to form the folds.
25. The combination with means for successively positioning and supporting signatures, of means for supplying fabric to the backs of the signatures and for securing it thereto, a shaft having a plurality of fabric 35 engaging devices thereon, a fabric guide coöperating with said devices, and means for rotating the shaft.
- 40 26. The combination with means for successively positioning and supporting signatures, of means for supplying fabric to the backs of the signatures and for securing it thereto, a rotary fold former having a plurality 45 of fabric engaging devices, a fabric guide coöperating therewith, a pair of slides which support the former and give it movements to advance the signatures after the securing means has acted, and means for 50 rotating the former to form the fold.
27. The combination with means for successively positioning and supporting signatures, of means for supplying fabric to the backs of the signatures and for securing it thereto, a rotary fold former having a plurality 55 of fabric engaging devices, a fabric guide coöperating therewith, a pair of slides which support the former and give it move-
- ments to advance the signatures after the securing means has acted, means for rotating the former to form the fold, a tension device, and a fold retaining device. 60
28. The combination with means for successively positioning and supporting signatures, of a shaft having a rectangular portion, a plurality of toothed plates mounted on said portion, means for supplying fabric to the backs of signatures and for securing it thereto, a guide coöperating with the plates, means for rotating the shaft to cause the plates to engage the fabric to form folds therein, and a pair of slides by which the shaft is given a movement to advance the signatures after the securing means has 65 acted. 70
29. The combination with means for successively positioning and supporting signatures, of a shaft having a rectangular portion, a plurality of toothed plates mounted on said portion, means for supplying fabric to the backs of signatures and for securing it thereto, a guide coöperating with the plates, means for rotating the shaft to cause the plates to engage the fabric to form folds therein, a pair of slides by which the shaft is given a movement to advance the signatures after the securing means has 75 acted, and a fold retaining device. 80
30. The combination with means for successively positioning and supporting signatures, of a shaft having a rectangular portion, a plurality of toothed plates mounted on said portion, means for supplying fabric to the backs of signatures and for securing it thereto, a guide coöperating with the plates, means for rotating the shaft to cause the plates to engage the fabric to form folds therein, a pair of slides by which the shaft is given a movement to advance the signatures after the securing means has 85 acted, and a fold retaining device. 90
31. In a book stitching machine, means for securing an attachment band to a series of sheets and a guide mounted on the machine frame, in combination with means pivoted to the frame for driving such band down into a loop after a series of sheets has 95 been stitched to said band. 100
- In testimony whereof, I have hereunto set my hand, in the presence of two subscribing witnesses. 110
